DESIGN FOR A SLIPPER

Aaron Runstein, Jersey City, N. J.

Application August 2, 1939, Serial No. 86,419

Term of patent 3½ years

To all whom it may concern:

Be it known that I, Aaron Runstein, a citizen of the United States of America, residing in Jersey City, county of Hudson and State of New Jersey, have invented a new, original, and ornamental Design for a Slipper, of which the following is a specification, reference being had to the accompanying drawing, forming part thereof.

Fig. 1 is a plan view of a slipper showing my new design.

Fig. 2 is a side elevational view thereof.

I claim:

The ornamental design for a slipper, substantially as shown.

AARON RUNSTEIN.
